FIG. 1.

UNITED STATES PATENT OFFICE

2,131,915

SECONDARY CLOCK

Bert Chapman, Endicott, N. Y., assignor to International Business Machines Corporation, New York, N. Y., a corporation of New York

Application May 28, 1936, Serial No. 82,221

2 Claims. (Cl. 58—26)

This invention relates to electric clocks and more particularly to electric clocks of the impulse type which are operated by electric impulses initiated at predetermined timed intervals 5 under control of a master clock.

It is the object of this invention to provide a new and improved construction of such a clock which will be simple and rugged, with a minimum number of parts and will be comparatively inexpensive to manufacture.

Other objects and advantages of this invention will be apparent from the specification and the accompanying drawing which shows one embodiment of this invention and where in similar 15 reference numerals indicate similar parts and wherein in the drawing:—

Fig. 1 shows a rear elevation of the clock movement.

Fig. 2 shows a detail of one of the parts of the 20 clock mechanism.

A mounting plate 5 is provided on which pole pieces 6 and 6' of a magnet 7 are mounted by means of screws 8 and 8'. The pole pieces are spaced outwardly from the mounting plate by 25 tubular spacers (not shown) between the plate and the pole pieces. A bracket 9 is rigidly secured to said pole pieces by said screws and provides a bearing for a shaft 10 which extends through the mounting plate 5 and is journaled therein. The shaft 10 is the minute hand shaft 30 of the mechanism and has mounted thereon a minute hand 11 and through the usual reduction gears 12 operates the hour hand 13.

Fixed to the shaft 10 is a ratchet wheel 14 which, in the preferred embodiment, carries 60 teeth whereby the rotation of the ratchet wheel rotates an amount equivalent to one tooth each minute causes it to make one revolution per hour. Cooperating with the ratchet wheel 14 is an actuating pawl 15 pivotally mounted on the arm 16 which is an integral part of the member 17, (Fig. 2). The member 17 is loosely mounted on the shaft 10 and is mounted immediately adjacent to the armature 18 also pivotally mounted 40 on the shaft 10. The armature 18 oscillates between the pole pieces 6 and 6'. The member 17 is provided with an arm 19 having lugs 20 and 21 formed over to grip the armature 18 and having an arm 22 extending in the opposite direction bearing against the side of the armature to prevent a twisting action about its bearing. The lug 21 has attached thereto a spring 23 which is anchored to a set screw on an adjustable collar 24 mounted on a stud which is fixed in the base 50 plate. By turning the collar on the pivot and

setting it with a set screw an adjustment in the tension of the spring 23 is obtained. A limit stop 25 is mounted on an arm 26 which is adjustably mounted on the mounting plate 5 by screws 27, the arm 26 having holes slightly larger than 5 the screw shanks to permit slight adjustment. Arm 28 of the member 17 has a formed-over portion which cooperates with said limit stop to limit the clockwise movement as viewed in Fig. 1 of the member 17 when the magnet is energized and 10 said limit stop cooperates with the pawl 15 in the counterclockwise movement of the member 17 upon deenergization of the magnet.

A retaining pawl 29 is pivotally mounted to a stud and cooperates with ratchet wheel 14 to prevent retrograde movement. A pair of contacts 30 is mounted on the base plate 5 and insulated therefrom and is operated by means of an insulated disk 31 mounted on an arm 32 which is pivotally mounted to a stud 35 in the base plate 20 5 and which has integral therewith an arm 33 which cooperates with a pin 34 mounted in the ratchet wheel 14. Upon each revolution of the ratchet wheel 14 the pin 34 strikes the arm 33 moving said arm, and the arm 32, clockwise, 25 thereby opening the upper and closing the lower of the pair of contacts 30. When the pin has passed by the arm, the spring action of the middle blade of the contacts rotates the arm counterclockwise to close the upper and open the lower 30 of the pair of contacts.

Normally when the magnet 7 is deenergized, the armature 18 is tilted slightly counterclockwise so that the pawl 15 rests against the limit stop 25 due to the tension of the spring 23. When an 35 electric impulse is received by said magnet, the armature 18 is moved clockwise to be pulled into the magnetic field between the pole pieces 6 and 6' thus rotating the member 17 clockwise and moving the pawl 15 to pick up the next adjacent 40 tooth to the right as viewed in Figure 1 and upon the next deenergization, the arm 17 and the armature attached thereto move counterclockwise carrying the ratchet wheel 14 a distance equivalent to one tooth and thereby moving the minute 45 hand of the clock a distance to indicate an advance of one minute.

While the fundamental novel features of the invention as applied to a single modification have been shown and described and pointed out, it will 50 be understood that various omissions and substitutions and changes in the form and details of the device illustrated and in its operation may be made by those skilled in the art without departing from the spirit of the invention. I in- 55

tend to be limited therefore only as indicated by the scope of the following claims.

What is claimed is:

1. A secondary clock including a front supporting plate, a rear supporting bracket and a minute shaft journaled therein, a ratchet wheel affixed to said shaft, a projecting member mounted on said ratchet wheel and synchronizing control means controlled by the rotation of said projection through its orbit, said synchronizing control means comprising contacts mounted on said front supporting plate, and a member pivotally mounted on said plate and having one arm cooperating with said contacts to control the position thereof and another arm extending into

the orbit of said projecting member and operable thereby.

2. An electric clock mechanism including a ratchet wheel and a pawl for advancing said wheel, a pawl carrier for said pawl pivotally mounted on an axis common to said ratchet wheel, a driving magnet, an armature associated therewith disposed lengthwise of said magnet and oscillatable about said axis, said pawl carrier having a U-shaped extension integral therewith to releasably engage a portion of said armature whereby the oscillation of said armature will cause said pawl carrier to oscillate to advance said ratchet wheel.
